CLAIM

The ornamental design for a facial cleaning apparatus with stand, as shown and described.

DESCRIPTION

FIG. 1 is a perspective view showing facial cleaning apparatus with stand of my design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a rear elevational view thereof as in FIG. 3 in which a portion has been encircled; and,

FIG. 9 is an enlarged rear elevational view of the encircled portion of FIG. 8.

The broken lines shown in FIGS. 1-5 and 7-9 illustrate portions of the facial cleaning apparatus with stand that form

(Continued)

no part of the claimed design. The outermost broken line on the bottom surface in FIG. 7 is also a boundary line.
